Johnston & Co.

His ATTORNEY

UNITED STATES PATENT OFFICE.

HENRY TIBONY, OF NEW YORK, N. Y.

COMBINATION PROTRACTOR AND COMPASS.

Application filed November 21, 1923. Serial No. 676,078.

To all whom it may concern:

Be it known that I, HENRY TIBONY, a citizen of the United States, residing at New York city, in the county and State of New York, have invented a new and useful Improvement in a Combination Protractor and Compass, of which the following is a specification.

This invention relates to improvements in a combination protractor and compass, intended for the use of workers in wood or steel, and has for its special object the providing of an instrument which can be accurately and quickly adjusted to any angle or circle desired, and also used in all kinds of shop and drafting work. As is obvious the construction is simple and economical and simple to handle with efficiency.

These objects are attained by the device shown in the drawings herewith in which:

Fig. 1 is a plan view of my device.

Fig. 2 is a longitudinal sectional view with part of the blade in elevation.

Fig. 3 is an edge view looking from the top of Fig. 1.

As shown in the drawings my device consists of a plate 5^b, with a rectangular flange 6^b slightly cut away at 15 to provide clearance for the thumb screw 7^b by which the blade 8^b is pivotally connected to the said plate. The end of the blade 8^b, which rests upon the plate 5^b is tapered off to form a fingerlike member adapted to indicate upon the graduated scale of the plate the precise angle at which the blade is disposed toward the plate.

The blade is also provided with a longitudinal slot 13 which terminates at its outer end in an enlarged aperture, through which the slideable index member 14 may be introduced so that it may travel along the said

slot. This member 14 also contains an aperture through which a pencil point or other marker may be inserted, to serve, if desired, in conjunction with the lower extremity of 45 the screw 7^b, as a convenient pair of dividers. The member 14 is made in two parts, the upper being a knurled nut and the lower a stud with a flange with an opening through the centre through which the index point 50 projects, the upper end of the stud being threaded for engagement with the knurled nut. The said tapered lowered extremity 11 of the screw 7^b could also be utilized to position the center of a circle of which the 55 circumference could be drawn by the marker inserted through the aperture in the slideable index member 14.

As shown in Figs. 2 and 3 the thumb nut 7^b and the pin may be formed separately 60 the lower end 11 of the latter being tapered and the upper end being threaded for engagement with the said thumb nut.

I claim:

In a universal gauge; a semi-circular plate 65 having a substantially rectangular flange along the straight edge thereof and the central portion of the plate being depressed below the upper face of the marginal portion; a blade having a free end, a finger end, a 70 graduated scale, and a longitudinal slot terminating in an enlarged aperture; an index member slidably mounted in the said slot and provided with an opening adapted to receive marking means; and means for pivotally attaching the said blade to the said plate comprising a pin having a tapered lower extremity and a threaded top portion, and a threaded thumb nut adapted to engage with the said top portion of the said 75 pin.

HENRY TIBONY.
